UNITED STATES PATENT OFFICE.

EDMUND S. CHURCH, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,004,848.

Specification of Letters Patent.

Patented Oct. 3, 1911.

Application filed June 11, 1906. Serial No. 321,232.

To all whom it may concern:

Be it known that I, EDMUND S. CHURCH, a citizen of the United States, residing at Dayton, in the county of Montgomery and 5 State of Ohio, have invented certain new and useful Improvements in Cash-Registers, of which I declare the following to be a full, clear, and exact description.

This invention relates to cash registers 10 and has among its objects to provide a machine of that class which will be of especial advantage in establishments where it is desired to indicate and account for the transactions of different classes separately.

15 Another object is to provide a machine of the so-called key operated type having instead of the usual tablet indicators, rotating indicators bearing a plurality of indicia, and separate flashes or shutters for each 20 indicator.

A further object is to provide a machine in which the indicators are normally in position to exhibit the numeral "one" through a slight opening, but which numerals "one" are concealed by a shutter, said 25 shutter being adapted to be moved from concealing position by a manipulative means such as a key.

An additional object is to provide means 30 for locking the keys in depressed position, thereby compelling the operation of a release key at each operation of the machine.

With these and incidental objects in view, the invention consists in certain novel 35 features of construction and combination of parts, the essential elements of which are set forth in appended claims and a preferred form of embodiment of which is hereinafter specifically described with reference to the 40 drawings which accompany and form part of this specification.

Of said drawings: Figure 1 represents a front elevation of the machine with part 45 of the cabinet broken away. Fig. 2 represents a vertical transverse section of the machine taken just inside of the right hand side frame. Fig. 3 is an enlarged detail view of the setting lever 33 showing a position of the gear 24 and the curved 50 locking plate 27 in dotted lines. Fig. 4 is a detail view of the full stroke device.

The machine to which these improvements are applied is of the so-called "detail adder" type which is now well known in 55 the art and is fully described and illustrated

in Letters Patent No. 384,158 issued on June 5, 1888 to J. H. Patterson *et al.* to which reference may be had for a more detailed description.

It may be said that the machine shown 60 comprises a series of keys 10 pivoted on a shaft 11 and having slotted rear ends adapted to be engaged by a key coupler 12. Each key is provided with a pawl 13 which operates on a primary adding wheel 14, at 65 each operation of the machine. The upper end of pawl 13 is so shaped that after it is operated and held in its upper position (by means to be later described) it will wedge between the teeth of the primary adding wheel 14 and the rim of the secondary adding wheel 22 thereby preventing the operation of the gears 24 and 23 while the keys 10 are depressed. This is for the purpose of compelling the operator to operate the 70 handle 34 before the keys 10 can be operated. Pivoted at 15 at the back of the machine is a retaining bar 16 which has a hooked nose 17 and a beveled lower end 18. The rear end of each key is provided with a 80 rearwardly projecting nose 19 which will engage the hooked nose 17 of the retaining bar 16 and will thereby cause the key 10 to be held in its operated position until released by a release key 20 the rear end of 85 which is beveled and which when operated strikes the bevel end 18 and cams the retaining bar 16 rearwardly to release said keys 10.

Each time the primary adding wheel 14 90 makes a complete rotation a projection 21 on its periphery engages one of the recesses of the secondary adding wheel 22 and advances said wheel 22 one step. Fast to the side of each wheel 14 is a gear wheel 23 95 which meshes with a gear wheel 24 loosely mounted on a rod 25. Fast to a rod 26 is a series of curved locking plates 27 there being one for each key. On the side of the plate 27 are a number of laterally projecting lugs 28 which are adapted to be engaged by a lateral projection 29 forming part of a spring catch 30 having an upwardly projecting pinch lever 31. This catch 30 is pivoted at 32 to a lever 33 which is loosely 105 pivoted on rod 25 and also has an upwardly extending handle 34. Thus it will be seen that when the handle 34 is grasped and the pinch lever 31 is operated that the lateral projection 29 will be carried away from 110

gagement with the lugs 28 on the curved locking plate 27 and will engage the teeth of the gear 24. When the handle is so operated and is then pulled downward the gear 24 will be rotated and through gear 23 will operate the primary adding wheel. Fast to and forming part of the lever 33 is a curved strip 35 upon the face of which are numerals from 2 to 9 inclusive and so arranged as to show through an opening 36 (see Fig. 1) in the casing of the machine to serve as an index to the operator. When the operator sees by the number appearing at said opening 36 that he has pulled the lever 33 to the desired extent he will then release the pinch lever 31 which will (by its spring) be forced out of engagement with the teeth of the gear 24 and into engagement with one of the locking lugs 28 thereby locking the lever 33 from return movement. Fast to the right hand end of the rod 26 is an arm 40 to which is loosely secured one end of a link 41 the other end being fastened to a release key 20. From this construction it will be seen that when the release key 20 is pressed, the rod 26 will be rocked and the curved locking plates 27 will also be rocked carrying the lugs 28 thereon out of engagement with the lug 29 of the spring catch 30 and allowing it to be returned to its normal position. To the lower end of each of the locking plates 27 is pivoted a spring pawl 45 which is so positioned as to be moved into engagement with the teeth of gear 24 when the rod 26 is rocked thereby preventing backward movement of the gear 24 when the levers 33 are being restored to zero.

It may be here noted that the movement of levers 34 is in each case one space less than the number caused to be indicated thereby by the rotary indicator. If this was not the case the subsequent operation of the key lever 10 to effect the transaction indication would cause an over registration as the depression of key lever 10 serves to add one unit to the counter wheel 14.

By the provision of a lever and a key for each kind of transaction, it becomes possible to indicate not only the amount but also the transaction characteristic. Clearly if the lever 34 was relied on to give the whole movement of the register, it would show the proper number on the indicator, but the indication of the characteristic would be wanting. By the provision of a key which operates the transaction characteristic indicator, it is possible to employ this indicator as a shield for the amount indicators, thereby compelling the depression of the transaction key. The action of the lever will then complete the addition of the proper amount on the register. It will thus be seen that the lever 34 must be connected to add one unit less than is indicated. It would, of course, be possible to provide a permanent indica-

tion above or below the amount indicators of the transaction characteristic, thereby doing away with the key mechanism, but no indication of the transaction would then be given, although, of course, the proper word would be immediately over or under the number. By the provision of a movable transaction indicator, and of means compelling its movement to exhibiting position, a much preferable indication is obtained. 75

From the above description it will be seen that the keys 10 and levers 33 form duplex operating devices for the movable elements of the registering mechanism.

Pivoted to the lower end of each of the levers 33 is a rearwardly extending link 46 the rear end of which is slotted to straddle a shaft 47. The rack 48 formed on the inside of said slot is adapted to engage a pinion 49 fast to shaft 47. Secured to shaft 47 is also another gear or pinion 50 with which meshes a rack bar 51 having rack teeth 52 at its lower end and rack teeth 53 at its upper end. The rack teeth 53 engage a pinion 54 secured to an indicator 55. It is plain from this construction that whenever the lever 33 is moved the indicator 55 will also be moved to display a figure on its periphery corresponding to the figure displayed at the opening 36. The lever 33 and other connecting parts are restored by a rod 60 which extends across all of the links 46 and engages projections 61 thereon. The rod 60 is supported at each end by bell crank arms 62 pivoted on a rod 63 and extending forwardly over key coupler 12. 95

When the key coupler 12 is raised it will swing the bell crank arms 62 on their pivot and withdraw the rod 60 away from the projections 61 and will tension a full stroke device to be described later. When the key coupler 12 is lowered a spring 64 will rock the arms 62 and restore the links 46.

Resting on the rear end of each key is a tablet indicator 65. This indicator extends upward in front of the circular indicators 55 thereby concealing them. Each indicator 65 has a rectangular opening 66 and a winged portion 67 and are so arranged as not to interfere with each other during their operation. Upon the winged portion 67 are printed words corresponding to the words on the front of the keys 10. There are two openings 68 and 69 in the cabinet, the opening 68 is to display the indication appearing on the circular indicators the opening 69 being to display the words on the tablet ends. From the above description it will be clear that whenever a key is depressed the tablet indicator 65 will be elevated to bring its rectangular opening 66 up to the opening 68 to reveal the indicating figure on the circular indicator 55 and its winged portion 67 up to the opening 69 to display its indication of the kind of article sold. 130

The circular indicators 55 are alined to their true indicating position by a plate 70 which is attached to an arm 80 of a flash 81 to be later described. This plate 70 has in its upper end a V shaped notch 71 which engages with V shaped teeth in a semicircular disk 72 fast to each indicator 55.

The above mentioned flash 81 is operated by a pin 82 on the release key 20. This flash is intended to conceal all indicators during the time they are being returned to their normal positions.

To insure a full upward stroke of the flash 81 and to hold it in its elevated position until all parts are in their normal position the mechanism shown in Fig. 4 is employed.

Fast to the shaft 63 is an upwardly extending arm 85 to the upper end of which is pivoted a laterally extending spring plunger 86. Loosely pivoted on shaft 63 is a sector 87 having teeth 88 on one of its edges adapted to be engaged by a projection 89 mounted on the flash arm 80. Secured to the upper end of sector 87 is a collar 90 through which passes the spring plunger 86. From this construction it will be seen that when the shaft 63 is rocked the spring of the plunger 86 will be tensioned and will force the teeth 88 of the sector 87 into engagement with the projection 89. As the flash arm 81 is now raised the projection 89 will ratchet along the teeth 88 and when at the end of its upper movement the sector will spring under projection 89 thereby holding the flash 81 in its elevated position until the shaft 63 is rocked to its normal position again which only occurs as all parts are restored to their normal position.

When the shaft 63 is so rocked the spring tension is released from the sector 87 which will swing back to its normal position allowing the flash to drop without the projection 89 contacting with the teeth 88.

The complete operation of the machine is as follows: Suppose it is desired to register and indicate one "soda", the key marked "Soda" will be depressed and its pawl 18 will move over the primary adding wheel one step but without actuating said wheel. The retaining bar 16 has in the meantime latched the key in its upper position. The key coupler 12 acting upon the bell crank lever 62 has tensioned the full stroke device shown in Fig. 4. An indicator 65 bearing the word "Soda" upon its winged portion 87 has also been raised to bring its rectangular opening 66 in front of the circular indicator 55 thereby exposing the figure "1" which is the normal position of said indicator and to bring its worded indication up to the opening 69. The operation being now completed the mechanism may be left in this condition (with the key depressed) to preserve the indication until the depression of

the release key 20 at the beginning of the next operation of the machine. On the other hand the release key may be depressed immediately after the depression of the keys 10 thereby restoring all parts to their normal position although this would destroy the indication. Now suppose the release key has been depressed in the previous operation and it is desired to register and indicate 6 drinks of coffee as indicated in Fig. 1. The lever 34 is grasped and the pinch lever 31 operated to disconnect the projection 29 from the curved locking plate 27 and force it into engagement with the gear wheel 24. The lever 34 will now be pulled downward until the figure 6 appears at the opening 36 (see Fig. 1) after which said lever is released allowing projection 29 to be forced from the gear 24 and into engagement with one of the lugs 28 of the plate 27 thereby holding lever 34 in its operated position. This movement of the lever 34 will through the link 46, pinions 49 and 50, rock bar 51, and pinion 54 set the indicator 55 to bring the figure "6" to indicating position. This movement has also through projection 61 and rod 60 rocked the shaft 63 thereby tensioning the full stroke device shown in Fig. 4. Now the key 10 marked "Coffee" will be depressed to raise the indicator 65 and bring the indication as shown in Fig. 1 to view. If the release key 20 is now depressed all parts will be restored to their normal position including the lever 34 which is released by the rocking of rod 26 and plate 27 as previously described.

While the form of mechanism here shown and described is admirably adapted to fulfil the objects primarily stated, it is to be understood that it is not intended to confine the invention to the one form of embodiment herein disclosed, for it is susceptible of embodiment in various forms all coming within the scope of the claims which follow.

What I claim is;

1. In a cash register, the combination with a registering device, of an indicator rotatable to expose any one of a plurality of indicia, a shutter for concealing said indicator, means for differentially rotating said indicator and said registering device, and a key for withdrawing said shutter and operating said registering device.

2. In a cash register, the combination with a plurality of indicating devices each rotatable to expose any one of a plurality of indicia, a plurality of shutters, one for each indicating device and normally concealing said devices, keys, equal in number to the shutters, and each serving to withdraw the corresponding shutter, and means for differentially operating the indicating devices.

3. In a cash register, the combination with

- indicators having a plurality of indicia but no zero indication, of operating means for differentially rotating said indicators, a shutter normally concealing each indicator and means for removing any desired shutter from concealing position.
4. In a cash register, the combination with a registering device, and a rotating indicator, of a combined concealing shutter and indicator, normally concealing said rotating indicator, means for differentially adjusting said rotating indicator, and a key for withdrawing said shutter and operating said registering device.
5. In a cash register, the combination with an indicator, of a transaction indicator normally concealing same, and means for exposing said first indicator by an exposure of the transaction indication of said second indicator.
6. In a cash register, the combination with a registering member, of a key and connections for operating said registering member to a constant extent at each actuation of said key, and a manipulative device and connections for differentially actuating said registering member.
7. In a cash register, the combination with indicating mechanisms, of a combined concealing shutter and indicator for said indicating mechanism, a manipulative device and connections for adjusting said indicating and registering mechanisms to differential extents, and means for adjusting said registering mechanism to a constant extent with connections whereby said means operates said combined shutter and indicator.
8. In a cash register, the combination with a counting member, of a key and connections for directly actuating said member through a single step of movement, and a hand operated element directly engaging said member and constructed to move it differentially.
9. In a cash register, the combination with a registering member, of a pivoted key and connections including a pawl for directly engaging said member and moving it a constant distance at each actuation of said key, a hand operated lever constructed to be given differential movement and a pawl carried by said lever and engaging said registering member.
10. In a cash register, the combination with a counting member, of a manipulative device and connections for operating said member to a constant extent, a second manipulative device and connections for operating said member to differential extents, and means for preventing coincident operation of said member from both manipulative devices.
11. In a cash register, the combination with an adding wheel and a rotary indicator, of means for setting same differentially, the resultant indication exceeding the amount added, a manipulative device, and means operated thereby for moving the adding wheel an amount equal to the excess of the indication over the preceding addition.
12. In a cash register, the combination with a registering member and a rotary indicator, of means for moving same differentially, the resultant indication exceeding the amount registered by a constant amount, a key, and means moved thereby for operating said registering member an amount equal to the constant excess of the indication over the preceding registration.
13. In a cash register, the combination with a registering member and an indicator, of means for moving same differentially, and a key for also moving said registering member, while allowing said indicator to remain stationary.
14. In a cash register, the combination with a registering member, and an indicating mechanism movable to expose any desired one of a plurality of indicia, means for differentially adjusting said registering member and indicating mechanism, a shutter for said indicating mechanism, and a manipulative device for withdrawing said shutter with connections from said device for actuating said registering member.
15. In a cash register, the combination with a registering member, and a rotating indicator, of means for moving said indicator and member differentially, a shutter for said indicator, and a manipulative device for moving said shutter to expose the indicator, and also moving said registering member a constant amount.
16. In a cash register, the combination with a registering member, of a lever, a device pivoted on said lever for actuating said registering member, a guide surrounding said registering member and with which said pivoted device is positioned to engage, and a release key for retracting said guide.
17. In a cash register, the combination with a registering member, of a lever and a pawl carried thereby for actuating said registering member, a guide adjacent said member having notches in which said pawl may engage, and a release key for retracting said guide.
18. In a cash register, the combination with a registering member, of a lever carrying a pawl for actuating said member, a pivoted arresting rack positioned to be engaged by said pawls, means for moving said pawl from engagement with said rack to engagement with said registering member, and means for withdrawing said rack from engagement by said pawl.
19. In a cash register, the combination with a concealing shutter, of a reciprocating bar carrying same and having a pawl, a pivoted arresting rack for compelling a full

stroke of said bar, and means for swinging said rack away from the path of said pawl.

20. In a cash register, the combination with an accounting member, of a differentially movable lever, a pawl on said lever adapted to engage said member, a member adjacent said accounting member and having locking notches for said pawl, means for withdrawing said notched member from said pawl, and means for resetting said lever to normal.

21. In a cash register the combination with an indicator, of an operating mechanism therefor, a concealing device for said indicator means for moving the latter into concealing position, and means for completing a full stroke of the concealing device, the said means supporting the device in concealing position until the indicator is returned to normal position.

22. In a cash register, the combination with a registering element, of a key for actuating said element, and an indicator bearing a transaction designation and having a cut away portion above said designation, also actuated by said key.

23. In a cash register, the combination with a registering element, a normally adjustable lever for differentially adjusting said registering element, an indicator actuated by said lever, a key and connections for also actuating said registering element by movement of said key, and an indicator actuated by said key, bearing a transaction designation and having a cut away portion

positioned to expose said lever actuated indicator.

24. In a cash register, the combination with a series of keys, and registering elements actuated thereby, of levers for also actuating said registering elements, indicating devices operated by said levers, shields, one for each indicating device, for preventing or permitting exhibition of said indicating devices, with connections whereby each key actuates an independent shield.

25. In a cash register, the combination with a registering mechanism comprising a plurality of movable elements, of duplex operating devices for each element, independent means for latching each of the operating devices in operated position, and means for unlatching said operating devices.

26. In a cash register the combination with a registering mechanism comprising a plurality of movable elements, of duplex operating devices for each element, an indicator for each element, and means operated by one of the operating devices for moving the indicator to indicate the sum of movement imparted to the corresponding registering element by both of the operating devices.

In testimony whereof I affix my signature in the presence of two witnesses.

EDMUND S. CHURCH.
